[57] CLAIM

The ornamental design for a battery pack or similar article, as shown and described.

DESCRIPTION

FIG. 1 is a front perspective view of the battery pack or similar article showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof; and

FIG. 7 is an opposite side elevational view thereof;

The terms left, right, front, rear, top, and bottom used to describe the orientation of the battery pack in the drawings are used for convenience and are not intended to limit the design to a particular orientation. As will be apparent, the battery pack of this invention may be used in any orientation.
